APPARATUS FOR COMMUNICATION SYSTEMS

Leland D. Whitelock, Wilkinsburg, Pa., assignor to The Union Switch & Signal Company, Swissvale, Pa., a corporation of Pennsylvania

Application December 5, 1936, Serial No. 114,439

19 Claims. (CL. 246—8)

My invention relates to apparatus for communication systems, and particularly to apparatus for communication systems utilizing a carrier frequency current and wherein transmission is accomplished in both directions on the same carrier frequency and over a single transmitting circuit.

I will describe two forms of apparatus embodying my invention, and will then point out the novel features thereof in claims.

A feature of my invention is the provision of novel and improved apparatus for communication systems wherewith an operating mechanism at one location is governed by control impulses transmitted from a remote location, and telephone communication is effected between the two locations. Another feature of my invention is the provision of novel and improved apparatus for systems of the type here involved whereby the operator at one location may break-in on the conversation of the operator at the other location. Still another feature of my invention is the provision of novel and improved apparatus for checking the integrity of the system to insure proper operation of the control mechanism when such operation is desired. Other features and advantages of my invention will appear as the specification progresses.

My invention is peculiarly useful for railway train communication systems where the train brakes are to be governed at two spaced locations on a train and telephone communication is to be effected also between the operators at the two locations. In such railway train communication systems a carrier frequency current modulated with voice frequencies is used for telephoning, the carrier current modulated by a single predetermined voice frequency or its equivalent is used for calling, and for brake control the carrier current coded in accordance with different brake control conditions is provided. The communication channel or transmitting circuit preferably includes the track rails in the manner described and claimed in the application for United States Letters Patent Serial No. 450,135, filed May 6, 1930, by L. O. Grondahl for Electric train signaling systems. The communication current is supplied to and received from the track rails through the medium of circuit elements electrically coupled with the track rails, switching apparatus being provided at each location for effectively coupling either the receiving or the transmitting apparatus with the track rails. In such systems as heretofore proposed, the operator actuates such switching apparatus manually, especially

during telephone communication, and there is no limit imposed on the length of time the equipment of a station can be held at the transmitting position. It is desirable that each operator may break-in upon the conversation of the operator at the other location in order that a message or signal relating to the control of the train may be delivered without delay.

In the accompanying drawings, Figs. 1 and 2, when taken together, constitute a diagrammatic view of one form of apparatus embodying my invention when applied to a railway train, brake control and telephone system. The apparatus of Fig. 1 is that to be installed on a train at the location of the supervising operator, and which location may be, for example, the locomotive of a freight train, the engineer being the supervising operator. The apparatus of Fig. 2 is that to be installed at another location on the train, and which location may be the caboose of a freight train. Fig. 3 is a diagrammatic, fragmental view of a modified form of the apparatus of Fig. 1.

In the following description, like reference characters refer to similar parts in each of the several views.

Although a particular application of my invention is here disclosed, it will be understood that the invention is not limited to communication systems for railway trains and is capable of application in many places. This one disclosure of the invention will serve to illustrate the many places where the invention will be useful.

In certain instances, circuit controlling contact fingers are shown remote from the relay windings which operate them. The relationship between these elements is indicated by the fact that each such circuit controlling contact finger bears a reference character corresponding to the reference character of the associated relay plus a distinctive numeral, and each such contact finger is illustrated in the position corresponding to the position of the relay.

Referring to Fig. 1, the reference character EV designates the usual engineer's brake valve capable of assuming the usual running and brake applying positions. As shown schematically, a circuit contact assembly is associated with the brake valve EV by virtue of the contacts 10 and 11 of the assembly being operatively connected with the brake valve handle 12. The contact 10 is adapted to make engagement with contacts 14, 15 and 16 in the lap, service and emergency positions of the brake valve, respectively. The con-

tact 11 is adapted to make engagement with an arcuate contact 13 in all three of the lap, service and emergency positions of the valve. The function of this contact assembly will appear as the 5 specification progresses.

The locomotive equipment includes a coder CD. The type of coder is immaterial and may be any one of several well-known types. It is deemed sufficient for this description to point out that 10 when the operating winding 17 of coder CD is energized the three code contact members 30, 40 and 50 are operated, the arrangement being such that contact member 30 engages a front contact 18 at the rate of 30 times per minute, the contact 15 member 40 engages a front contact 19 at the rate of 40 times per minute, and the contact member 50 engages a front contact 20 at the rate of 50 times per minute. It will be understood that my invention is not limited to these specific 20 rates of operation of the coder contacts and that other rates may be selected if desired. A relay CX is associated with coder CD for governing the operation thereof. Relay CX is controlled over a circuit that extends from the B terminal of 25 any convenient source of current such as a battery not shown, winding of relay CX, contact 11-13 of the contact assembly, wire 21, back contact 22 of a relay TZ to be referred to later, and thence to the C terminal of the same source 30 of current. The energizing circuit for the coder CD includes battery terminal B, front contact 23 of relay CX, winding 17 of coder CD, contact 11-13, wire 21, back contact 22 and to the C battery terminal. It follows that with the brake 35 valve EV operated to a running position the relay CX is deenergized and the coder CD is inactive, but that operation of the brake valve EV to a brake applying position causes the relay CX to be energized and the coder CD to be active. The 40 manner whereby the code contacts 30, 40 and 50 are effective to establish different brake control codes will appear when the operation of the system is described.

The transmitting apparatus on the locomotive 45 includes an oscillator OS1, a microphone M, a modulator MD, a band pass filter BPF, and a power amplifier PA, as well as control and sending circuits associated therewith.

The microphone M, during periods when tele- 50 tron tube type, the oscillating circuit of which includes condensers 24, 25, and 26. The current generated by the oscillator OS1 is delivered to the modulator MD over wires 27 and 28, and which modulator may be any one of several types and 55 will be here considered as being a balanced electron tube type, such as disclosed in my copending application for United States Letters Patent Serial No. 29,338, filed July 1, 1935.

The microphone M, during periods when tele- 60 phone conversation is not being carried on, is preferably carried on a rack or a hook not shown and has attached thereto a handle 65 to facilitate its being brought close to the person speaking. Two contacts 66 and 67 are operatively connected 65 with the microphone as indicated by a dotted line, the arrangement being such that contacts 66 and 67 occupy the positions illustrated by solid lines when the microphone is placed on the hook and are operated to the positions indicated by 70 dotted lines when the microphone is lifted off the hook. The microphone M is connected over wires 29 and 31 with the modulator MD to effect modulation of the carrier supplied from the oscillator OS1 by the voice frequencies produced 75 by speaking into the microphone. The side band

frequencies resulting from such modulation are supplied to the input side of the band pass filter BPF over wires 32 and 33, the carrier being suppressed by the balanced arrangement of the circuits of the modulator. The filter BPF is proportioned and adjusted to suppress one side band and to pass the other. To assist in understanding my invention, I shall assume that the lower side band is suppressed and the upper side band is passed, it being understood, of course, that the 1 upper side band may be suppressed and the lower side band passed if desired. The output side of the filter BPF is connected with the input terminals of the power amplifier PA over wires 34 and 35. For reasons to appear hereinafter, the 1 wires 32 and 35 are preferably grounded as shown at 86 and 87, respectively, and the wires 33 and 34 are connected over a front contact 9 of a relay AX. Thus, the output of the modulator MD is ordinarily passed to the power amplifier through 2 the band pass filter BPF, but at such times as the relay AX is energized and its front contact 9 closed the output of the modulator is bypassed around the filter to the power amplifier.

The power amplifier PA may be any one of 2 several types such as, for example, two power electron tubes connected in the push-pull arrangement. Hence, the carrier current supplied to the input terminals of power amplifier PA is supplied to a sending circuit and in turn to a transmitting circuit amplified to a relatively high energy level. In this instance, the sending circuit may be traced from the lower right-hand terminal of amplifier PA over wire 36, rear truck wheels 37, track rails 38, forward truck wheels 39, and wire 41 to the upper right-hand terminal of the power amplifier. Current thus supplied to the track rails which form a part of the transmitting circuit produces an electromotive force therein, which in turn causes current to flow in the rails in both directions from the locomotive in the well-known manner. The oscillator OS1, modulator MD, filter BPF and power amplifier PA are shown conventionally in order to simplify the drawings as much as possible, since the specific structure of each of these devices forms no part of my present invention.

The operation of the transmitting apparatus is controlled by three relays PR, CR, and AX. Relay PR when picked up to close its front contact 42 completes a connection by which plate voltage is supplied from the BH terminal of any convenient source of current such as a generator not shown to the plate circuits of the tubes of the oscillator OS1 and the modulator MD, the plate circuits being completed through ground electrodes 88 and 89. The relays CR and AX govern the oscillating circuit associated with oscillator OS1, the relay CR completing at its back contact 43 a connection by which the condenser 26 is interposed in the circuit, and the relay AX completing at its back contact 44 a connection by which the condenser 25 is interposed in the circuit. The relay CR also governs the connection of the modulator MD. With relay CR released, closing its back contact 57, a connection is completed from the modulator MD by which a balanced arrangement of the circuits thereof is effected, but when relay CR is picked up, closing its front contact 58, the connection for the modulator is shifted so that a parallel arrangement of its circuits is effected. Relay AX also controls at front contact 9 the bypass around the filter BPF as described hereinbefore.

These three relays PR, CR and AX are them- 7

5 selves governed over a circuit network. A push button PB₁ when operated to close a contact 45—46 completes a circuit extending from the B terminal over back contact 1CX of the relay CX, 5 contact 45—46, wire 47, winding of relay PR and to the C terminal, and the relay PR is energized. Operation of a push button PB₂ completes a circuit extending from the B battery terminal over back contact 1CX, contact 48—49 of push button 10 PB₂, wire 51, windings of relays CR and PR in series and to the C terminal, and the two relays CR and PR are energized in series. Operation of a push button PB₃ completes a circuit extending from the B terminal over back contact 15 1CX, contact 52—53 of push button PB₃, wire 54, windings of relays AX, CR and PR in series and to the C terminal, and the three relays are energized in series. The three control relays may also be energized in series by means of another 20 circuit that extends from B terminal over front contact 55 of a relay TR, wires 56 and 54, the windings of the three relays in series, and to the C terminal. Again, these three relays may be energized over B terminal, front contact 121 of 25 relay CX, wires 56 and 54, windings of the relays in series, and to the C terminal. Operation of either push button PB₁ or PB₂ also completes a circuit easily traced by which a relay 124, to be referred to later, is energized, the circuit including contact 136—137 of push button PB₁ or 30 contact 138—139 of push button PB₂.

35 Operation of the push button PB₁ to energize relay PR leaving the two relays AX and CR de-energized, establishes the telephone condition for the transmitting apparatus. Under this tele- 40 phone condition the oscillator OS₁ and modu- lator MD are rendered active, the frequency of the carrier delivered by the oscillator being de- termined by the three condensers 24, 25 and 26 in parallel, and the modulator MD being in its bal- 45 anced arrangement. To better illustrate my in- vention, I shall assume that the frequency of the carrier current when the three condensers 24, 25 and 26 are in circuit is 7000 cycles per second. 50 Taking the voice frequency range to extend from 600 to 2000 cycles per second, the addition and subtraction of the voice frequencies with the carrier of 7000 cycles produces an upper side band extending from 7600 to 9000 cycles and a lower 55 side band extending from 6400 to 5000 cycles. As- suming the band pass filter BPF to be proportioned to pass the upper side band only, it is clear that operating the push button PB₁ and speak- ing into the microphone M is effective to cause a carrier telephone current to be supplied to the 60 track rails of the transmitting circuit, the cur- rent flowing in the track rails in both directions from the locomotive.

65 Operation of push button PB₂ to pick up re- lays CR and PR leaving relay AX deenergized, es- tablishes the calling condition of the trans- mitting apparatus. This setup of the control re- 70 lays is effective to render the oscillator OS₁ and the modulator MD active, the modulator being now in its parallel arrangement and the fre- quency of the carrier generated by oscillator OS₁ being determined by the two condensers 24 and 25. I shall assume that the frequency of the 75 calling current is 8050 cycles, that is, it is the equivalent of the original carrier of 7000 cycles modulated by a voice frequency of 1050 cycles. The modulator MD being now in its parallel ar- 75 arrangement, the current of 8050 cycles is deliv- ered through the modulator MD and the band

pass filter BPF to the amplifier PA and thence to the track rails.

80 Operation of push button PB₃ to energize all three of the control relays AX, CR and PR es- tablishes the break-in condition of the trans- 85 mitting apparatus. Under this setup of the con- trol relays the oscillator OS₁ and the modulator MD are made active, the modulator being in the parallel arrangement, and the frequency of the 90 carrier current delivered by the oscillator OS₁ being determined by the condenser 24 alone. The 95 condenser 24 is so proportioned that the os- cillating circuit now delivers a carrier current of a frequency higher than the upper side band of the telephone current referred to hereinbe- fore. For example, the carrier current now de- 100 livered by the oscillator OS₁ may have a fre- quency of 13,000 cycles per second. Since the 105 picking up of relay AX completes the bypass 110 around the filter BPF, this break-in carrier cur- 115 rent of 13,000 cycles is delivered through mod- ulator MD to the power amplifier PA with little 120 attenuation and is then in turn supplied to the 125 track rails. Since the circuit for energizing the 130 three relays AX, CR and PR in series is com- 135 pleted at the front contact 55 of relay TR and 140 also at the front contact 121 of relay CX, it fol- 145 lows that an impulse of current of 13,000 cycles 150 is delivered to the track rails when either of the 155 relays TR or CX is energized. As will appear 160 hereinafter, impulses of current of 13,000 cycles 165 are supplied to the track rails by virtue of 170 operation of the relays TR and CX for providing 175 check impulses and brake control impulses, re- 180 spectively.

185 The locomotive receiving apparatus preferably 190 includes an inductor coil CC, two band pass fil- 195 ters F₁ and F₂, an amplifier demodulator AD, 200 an oscillator OS₂, an audio amplifier AM, a loud 205 speaker LS and a check circuit SC. The ampli- 210 fier demodulator AD, oscillator OS₂ and audio 215 amplifier AM are each shown conventionally 220 only for the sake of simplicity since each of these 225 devices may take any one of several well known 230 forms and the specific structure thereof is not 235 a part of the present invention.

240 The inductor coil CC is preferably of the air 245 core type and is electrically coupled with the 250 transmitting circuit by being mounted on the lo- 255 comotive in inductive relation with the track 260 rails. For example, the coil CC may be mounted 265 in a vertical plane on the top of the locomotive 270 tender. The inductor coil CC is connected with 275 the input side of the filter F₁ over wires 59 and 280 60, a back contact 125 of the relay 124 being 285 interposed in the wire 59. The output side of 290 the filter F₁ is connected over wires 68 and 69 295 with the input terminals of the amplifier de- 300 modulator AD. Carrier current is supplied to 305 the amplifier demodulator AD for mixing with 310 the incoming carrier current by the oscillator 315 OS₂ and the output terminals of the demodulator 320 AD are connected with the input side of the 325 filter F₂, the output side of which filter is 330 connected with the input terminals of the ampli- 335 fier AM. The loud speaker LS and the check circuit 340 SC are connected with the output terminals of 345 amplifier AM in parallel, the connection to the 350 loud speaker including wires 70 and 71. The 355 check circuit SC includes a condenser 61, reactor 360 62 and the contact 67 operated by the micro- 365 phone M. A portion of the reactor 62 is con- 370 nected with the input terminals of a rectifier 63, 375 the output terminals of which are connected with 380 the operating winding of a relay 64.

Since, as stated hereinbefore, transmission is accomplished on the same carrier frequency in both directions, the filter F_1 is proportioned to pass a band of frequencies extending from 7600 to 9000 cycles and the oscillator OS_2 is effective to supply a carrier of 7000 cycles. The filter F_2 is proportioned to pass a band of frequencies extending from 600 to 2000 cycles and the check circuit SC is proportioned to be sharply tuned at 1050 cycles. Hence, a carrier telephone current of the range of 7600 to 9000 cycles flowing in the track rails at the locomotive induces an electromotive force in the coil CC which is passed by the filter F_1 and demodulated at the amplifier demodulator AD , producing in the output of the demodulator voice frequencies of a range of 600 to 2000 cycles and other products of demodulation. The filter F_2 is effective to pass this range of voice frequencies and suppress the other products of demodulation. The voice frequencies passed by filter F_2 and amplified at the amplifier AM and reproduced by the loud speaker LS , the check circuit SC being non-responsive, since the energy of the telephone current corresponding to the frequency to which the check circuit is responsive is negligible. In the event a calling current of 8050 cycles flows in the track rails an electromotive force is induced in the coil CC which is passed by the filter F_1 and demodulated to produce a frequency of 1050 cycles in the output of the demodulator. This frequency is passed by filter F_2 and amplified by the amplifier AM and is effective to produce a note at the loud speaker and to energize the relay 64 through the medium of the check circuit SC , since the check circuit is sharply tuned at this frequency of 1050 cycles.

The locomotive is also equipped with indicating and checking apparatus which consists of a group of relays $1X$, $2X$, TR , TX and TZ , and an indicator lamp L . The relay $1X$ is controlled by means of a circuit extending from B battery terminal over front contact 72 of relay 64 , wire 13 , winding of relay $1X$, back contact 22 of relay TZ and to the C terminal. The relay $2X$ is energized over a circuit including terminal B , winding of relay $2X$, front contact 14 of relay $1X$, back contact 22 and to the C battery terminal. The lamp circuit includes the front contact 75 of relay $2X$, the lamp L , wire 21 , and the back contact 22 of relay TZ . The relay $1X$ is of the ordinary acting type but the relay $2X$ is slow releasing in character. Relays TR and TX comprise a timing means and are operated in parallel being energized over a circuit including E battery terminal, windings of the two relays TR and TX in parallel, back contact 76 of relay CX , back contact 17 of relay $1X$, wire 18 , contact 66 of the microphone, wires 19 and 21 , back contact 22 of relay TZ and to the C terminal. The relay TR controls the three relays CR , PR and AX in the manner described hereinbefore, and the relay TX controls the relay TZ , the pickup circuit for relay TZ being completed at the front contact 80 of the relay TX . Relay TZ is provided with a stick circuit which includes its own front contact 81 and the normally closed contact of a push button 82 . The manner whereby these indicating and checking relays function to control the lamp L and to produce checking impulses will appear when the operation of the apparatus is described.

Referring to Fig. 2, the caboose is provided with transmitting apparatus which includes an oscillator OS_1 , a microphone M , a modulator

MD , a filter BPF and a power amplifier PA , and each of which devices is similar to the corresponding device of the locomotive equipment. The transmitting apparatus on the caboose is governed by two relays PR and CR , similar to the corresponding relays of Fig. 1, and which relays are also controlled in a similar manner, the relay PR being energized alone when a push button PB_4 is operated and the two relays CR and PR being energized in series when a push button PB_5 is operated. The two relays PR and CR of Fig. 2 may also be energized in series over a front contact 83 of a relay 64 to be referred to later. The relay PR controls at its front contact 85 a supply of plate voltage for the tubes of the oscillator OS_1 and of the modulator MD . The relay CR governs the oscillating circuit and the connections for the modulator. With relay CR released, closing its back contacts 90 and 93 , the condenser 92 is interposed in the oscillating circuit and the circuits of the modulator MD are arranged in a balanced arrangement. When relay CR is energized opening back contacts 90 and 93 , and closing front contact 94 , the condenser 92 is disconnected from the oscillating circuit and the modulator circuits are switched to a parallel arrangement. The output terminals of the power amplifier PA of Fig. 2 are connected with a sending circuit that includes the truck wheels 95 and 96 at the opposite ends of the caboose, and hence are directly coupled with the track rails of the transmitting circuit. To agree with the previously assumed frequencies for the apparatus on the locomotive, the caboose oscillator OS_1 is adjusted to generate a carrier frequency of 7000 cycles when the two condensers 91 and 92 are interposed in the associated oscillating circuit and to generate a carrier frequency of 8050 cycles when the condenser 91 alone is included in the oscillating circuit.

It is clear that operating the push button PB_4 and speaking into the microphone M is effective to supply to the track rails a carrier telephone current having the frequency range of 7600 to 9000 cycles, and operating push button PB_5 is effective to cause a calling current of 8050 cycles to be supplied to the track rails. Again, energization of relay 64 closing its front contact 83 is effective to supply a current of 8050 cycles to the track rails, and which latter current is utilized as a return check impulse in a manner shortly to appear.

The caboose is provided with receiving apparatus similar to the receiving apparatus of Fig. 1 except that an input transformer T_1 , an auxiliary inductor coil BC , a frequency conversion unit designated as a whole by the reference character FC , and brake control equipment are added.

The inductor coil CC of Fig. 2 is preferably mounted on the caboose roof on a vertical plane to be in inductive relation with the track rails and is interposed in a receiving circuit including back contact $2PR$ of relay PR , the upper portion of the primary winding 97 of transformer T_1 and condenser 98 . This receiving circuit is tuned to efficiently pass a current having a range of frequencies extending from 7600 to 9000 cycles.

The output of the amplifier AM of Fig. 2 is delivered to the loud speaker LS , a check circuit SC_1 and a brake control circuit BCC in parallel. The check circuit SC_1 includes a condenser 113 , a reactor 114 and a contact 115 operated by the microphone M , a portion of reactor 114 being connected with the winding of relay 75 .

84 through a rectifier 116. This check circuit SC1 is tuned sharply to respond to a current of 1000 cycles whereas the check circuit on the locomotive is tuned to respond to a current of a frequency of 1050 cycles. The brake control circuit BCC includes a reactor 119, a condenser 120, and the input side of a rectifier 118, the output terminals of rectifier 118 being connected with three code selectors S30, S40 and S50 in parallel. This brake control circuit is proportioned to respond to a current of 1000 cycles. The code selectors S30, S40 and S50 may be any one of several different types and it is deemed sufficient to point out that selector S30 is responsive only to a current interrupted or coded at the rate of 30 times per minute, the selector S40 is responsive only to current coded at the rate of 40 times per minute, and the selector S50 is responsive to current coded at the rate of 50 times per minute. Brake controlling magnets LM, SM and EM are connected with the selectors S30, S40 and S50, respectively. It follows that magnet LM is energized when a current of 1000 cycles coded at the rate of 30 times per minute appears in the output of the amplifier AM, magnet SM is energized when such current is coded at the rate of 40 times per minute and magnet EM is energized when the current is coded at the rate of 50 times per minute. The magnets LM, SM and EM may be used to govern electropneumatic brake valves not shown in the usual manner or they may be employed to govern an indicator for indicating to an operator the manner in which he is to operate a manually operated brake controlling valve. To check the position of the brake controlling apparatus the magnets LM, SM and EM are provided with back contacts 128, 129 and 130, respectively.

40 The auxiliary inductor coil BC is preferably mounted on the caboose roof in inductive relation with the track rails and hence with the transmitting circuit, and is connected to the frequency conversion unit FC, the immediate circuit extending from the lower terminal of coil BC over wire 99, a portion of winding 100 of a transformer T3, condenser 101 and wire 102 back to the opposite terminal of coil BC. This circuit is tuned to efficiently pass a carrier current having a frequency of 13,000 cycles. That is, the auxiliary coil BC is effective to receive the break-in and break control current supplied by the transmitting apparatus of the locomotive. The winding 100 of transformer T3 is interposed in a connection between a control grid 105 and the cathode element 108 of an electron tube 103, the connection being completed through the ground electrodes 104 and 111. An oscillator OS3 is connected between a second control grid 107 and the cathode element 108 of tube 103, while the plate circuit of the tube includes the primary winding 109 of a coupling transformer T2.

To agree with the frequency of 13,000 cycles to be received by the auxiliary inductor coil BC, the oscillator OS3 of the frequency conversion unit would preferably deliver a carrier current of 5000 cycles. The product of mixing the local carrier of 5000 cycles with the incoming current of 13,000 cycles is the addition and subtraction frequencies, namely, 18,000 cycles and 8000 cycles. That is, frequencies of 18,000 and 8000 cycles are caused to appear in the plate circuit of tube 103 in response to a current of 13,000 cycles received by the inductor coil BC, and these frequencies in the plate circuit are effective to induce an elec-

tromotive force of corresponding frequencies in the secondary winding 110 of the coupling transformer T2. The secondary winding 110 is connected with the lower portion of the primary winding 97 of transformer T1 over a simple circuit easily traced, a condenser 111 being associated with this circuit to tune the circuit to maximum efficiency at 8000 cycles and thereby partially eliminate the other components of the frequency conversion. Hence, as a result of the frequency conversion, an electromotive force of 8000 cycles is induced in the secondary winding 112 of transformer T1 and is applied to the input side of the filter F1. Since 8000 cycles falls within the pass band of the filter F1 (7600 to 9000), this current is passed to the demodulator where it is mixed with the local frequencies of 7000 cycles supplied by the oscillator OS2, with the result that a current of 1000 cycles appears in the output of the demodulator. Since 1000 cycles falls within the pass band of the filter F2 (600 to 2000), this current is passed to the amplifier AM and is effective to operate the relay 84 of the check circuit SC1 and to effectively energize the brake controlling circuit BCC, as well as to sound a corresponding note at the loud speaker LS.

Consequently, electromotive force induced in the inductor coil CC in response to the carrier telephone current flowing in the transmitting circuit when applied to the receiving apparatus of Fig. 2 results in the reproducing of the voice frequencies at the loud speaker. Electromotive force induced in the coil CC in response to a calling current of 8050 cycles flowing in the transmitting circuit when applied to the receiving apparatus of Fig. 2 results in a note corresponding to a voice frequency of 1050 cycles being sounded at the loud speaker. Electromotive force induced in the auxiliary coil BC in response to the current of 13,000 cycles flowing in the transmitting circuit when applied to the frequency conversion unit FC and then in turn to the receiving apparatus results in effectively influencing the check circuit and the brake control circuit, as well as sounding a corresponding note at the loud speaker.

In describing the operation of the apparatus of Figs. 1 and 2, I shall first consider the operations that take place in exchanging check impulses between the locomotive and the caboose when the engineer's brake valve EV is set at a running position and the two microphones M are both placed on their respective hooks. At the start the timing relays TR and TX and the relay IX, as well as the relay CX are down. Current is now supplied to the timing relays TR and TX over the back contacts 11 and 16 of relays IX and CX, respectively, and the timing relays are set into operation. The relay TR shortly picks up, closing front contact 55, since the pickup period of relay TR is of the order of 5 seconds, whereas the pickup period of relay TX is of the order of 1 minute. With relay TR picked up, the control relays AX, CR and PR are energized in series, with the result that the transmitting apparatus is rendered active to supply a current of 13,000 cycles to the track rails, and which current forms an outgoing check impulse that remains in effect until a return check impulse is received at the locomotive. The 13,000 cycle current induces an electromotive force in the auxiliary inductor coil BC at the caboose, which electromotive force when passed by the frequency conversion unit FC and applied to the receiving

apparatus on the caboose produces a current of 1000 cycles in the output of the associated amplifier AM. As a result of this current of 1000 cycles the relay 84 is energized and picks up closing its front contact 83 after a slight slow picking up period, and the loud speaker LS sounds a corresponding note, the brake control magnets LM, SM and EM being non-responsive to the current since the current is not coded. The relay 84 on picking up energizes the associated control relays CR and PR, with the result that the caboose transmitting apparatus is rendered active to supply to the rails a current of 8050 cycles and which current forms a return check impulse. The current of 8050 cycles induces an electromotive force in the locomotive coil CC, which electromotive force when applied to the locomotive receiving apparatus appears in the output of the associated amplifier AM as a current of 1050 cycles, with the result that the relay 64 is energized and a corresponding signal is sounded by the loud speaker. Relay 64 when picked up to close front contact 72 causes relay 1X and in turn the relay 2X to be energized. Relay 2X on picking up completes the circuit for the lamp L and the lamp is now illuminated to indicate to the engineman that the apparatus is in operating order. When relay 1X picks up to open back contact 77 the timing relays TR and TX are deenergized and restored to their initial positions, the relay TR being slightly slow releasing in character. When relay TR releases, the associated control relays AX, CR and PR are deenergized and the outgoing check impulse ceases. With the discontinuing of the outgoing check impulse the relay 84 of the caboose apparatus is deenergized and releases to discontinue the return check impulse, with the result that the relay 1X on the locomotive is at once de-energized. The relay 2X, however, remains picked up since it is slow releasing in character and the lamp L remains illuminated. With the release of relay 1X the circuit for the timing relays TR and TX is again closed and the operation is repeated. It follows that the apparatus automatically exchanges impulses between the locomotive and the caboose once for each operating period of the timing relay TR. The relay 2X is provided with a release period that is somewhat greater than the operating period of relay TR and hence remains picked up from one check impulse to the next, and the lamp L is continuously illuminated as long as the check impulses are periodically exchanged.

Since the relay TX is reset at each exchange of impulses it is not operated to close its contact 80 as long as the system is in proper operating order. In the event of a failure in the apparatus and no check impulse is received at the locomotive, the operation of the relay TX is continued and at the end of one minute closes the contact 80 and energizes the relay TZ, which relay is then retained energized over its stick circuit. With relay TZ picked up connection with the C terminal of the current source is broken at the back contact 22 and current is removed from the brake controlling equipment, the lamp L being now dark to indicate to the engineman that the brake controlling equipment is out of order. It is to be noted that if the fault is of short duration and the check impulses are reestablished the lamp L is again illuminated and the operation of exchanging check impulses is reestablished. However, when the fault is of a relatively long period, that is, a period equal to the operating time

of the relay TX, the apparatus is automatically cut out of service through the medium of the relay TZ. Should the engineman desire to re-establish the operation of the apparatus after it has once been cut out through the medium of relay TZ, he can do so by operating the push button 82.

Assuming now the check impulses are being exchanged in the manner recited above and the engineman makes a brake application by operating the brake valve EV to the service position closing contacts 10-15 and 11-13, the relay CX is at once picked up closing front contact 23 to start operation of the coder CD, opening back contact 16 to discontinue the operation of the timing relays, and closing front contact 121 to energize the control relays. Under these circumstances, the transmitting apparatus on the locomotive is rendered active to supply a current of 13,000 cycles. Each time the code contact 19-40 is closed a shunt path is completed for the oscillating circuit of oscillator OS1 and the generated carrier current is interrupted or coded. This shunt path includes wire 122 connected to the upper right-hand terminal of the oscillating circuit, contact 10-15, code contact 19-40 and wire 123 to the lower right-hand terminal of the oscillating circuit. It follows that the outgoing current of 13,000 cycles is interrupted or coded at the coded rate of 40 times per minute as long as the brake valve EV is retained at the service position.

The electromotive force now induced in the inductor coil BC at the caboose, after being converted by the frequency conversion unit FC and applied to the receiving apparatus, produces in the output of the amplifier AM a current of 1000 cycles coded at the rate of 40 times per minute, with the result that the brake magnet SM is energized. It is to be pointed out that the relay 84 does not respond to this coding current since its circuit is broken by the back contact 129 of magnet SM and the relay 84 is slightly slow to pick up in character. It is clear that operation of the brake valve EV to either the lap position or the emergency position causes a similar operation of the apparatus except for the fact that the outgoing current is coded at the rate of 30 or 50 times per minute and either the brake controlling magnet LM or EM is selected. Restoring the brake valve EV to the running position deenergizes the relay CX and the operation of automatically exchanging check impulses is re-established.

In the event the engineman desires to initiate telephone communication, he would first remove his microphone from the hook, opening contacts 66 and 67 and thereby discontinuing the check impulses. The engineman would next operate the push button PB2 to pick up the relays CR and PR and set the transmitting apparatus in a condition for supplying to the track rails a calling current of 8050 cycles, the current continuing uninterrupted as long as the push button PB2 is operated. Since the relay 124 is also energized in response to operation of the push button PB2 the locomotive receiving circuit is held open and made non-responsive to the outgoing calling current. The electromotive force induced in the inductor coil CC on the caboose in response to this calling current, when applied to the associated receiving apparatus, produces a current of 1050 cycles in the output of the amplifier AM, with the result that a corresponding signal is sounded at the loud speaker. However, neither the check

circuit SC1 nor the brake control circuit BCC is effectively influenced by this calling current since they are tuned to respond to a current of 1000 cycles. This audible signal produced at the loud speaker at the caboose is an indication to the caboose operator that telephone communication is desired and he would at once remove his microphone from the hook prepared to telephone. After a suitable interval the engineman would release his push button PB2 and discontinue the calling current. The caboose operator would now respond by operating his push button PB4 and speaking the usual "hello" signal in the microphone. From this point on, telephone conversation would be carried on by the proper operation of the push buttons PB1 and PB4, each operator moving his push button when he wishes to speak and releasing his push button when he wishes to receive.

20 If the operator at the caboose desires to initiate telephone communication, he would remove his microphone from the hook, opening contact 115 in the check circuit and thereby discontinue the return check impulses. The caboose operator 25 would then operate his push button PB5 to pick up the relays CR and PR and render the caboose transmitting apparatus active to supply a calling current of 8050 cycles. The electromotive force induced in the inductor coil CC on the locomotive in response to this calling current is effective to produce after demodulation a current of 1050 cycles in the output of the amplifier AM, which current creates a corresponding signal at the loud speaker LS and energizes the relay 64 30 of the check circuit. Relay 64 in turn causes the relay 1X to be energized, which relay on picking up renders the locomotive apparatus inactive to further continue the supply of check impulses. The prolonged signal at the loud speaker LS on the locomotive would indicate to the engineman that telephone communication is desired and he would at once remove his microphone from the hook ready to telephone. After a suitable period the operator in the caboose 45 would release the push button PB5 and discontinue the calling current. From this point on, telephone conversation would be effected in the same manner as before described.

In the event the engineman desires to break 50 in on the conversation of the caboose operator, the engineman would operate the push button PB3 and send out from the locomotive a current of 13,000 cycles. Although the caboose apparatus is now in a transmitting condition, the electromotive force induced in the auxiliary inductor coil BC in response to the 13,000 cycle current would be converted by the frequency conversion unit FC and applied to the receiving apparatus and produce a non-coded current of 1000 cycles 55 in the output of the amplifier AM. Such a signal at the loud speaker LS would indicate to the caboose operator that the engineman desired to break in upon his conversation and he would set his apparatus in a receiving condition. In the event an emergency arose during the telephone conversation of the caboose operator that required an application of the train brakes, the engineman would operate his brake valve to the desired position with the result that the locomotive apparatus would send out control impulses of 13,000 cycles coded according to the position of the brake valve. This current of 13,000 cycles would be received by the caboose inductor coil BC and would be effective to energize the 70 corresponding brake magnet, notwithstanding 75

the fact that the caboose operator is transmitting a telephone conversation at the same time.

It is to be pointed out that the inductor coil BC would be little influenced by the usual telephone current of the frequencies of 7600 to 9000 cycles because of the tuning of the circuit to which it is connected. The small portion of 7600 to 9000 cycle current that is induced in the coil BC and hence applied to the frequency conversion unit would cause no interference in the 10 receiving apparatus as the lower products of frequency conversion would be 2600 to 4000 cycles and these frequencies would be cut off at the filter F1 since they are outside of the pass band of that filter. The higher products of frequency 15 conversion would be 12,600 to 14,000 cycles and this band of frequencies is also outside of the pass band of the filter F1.

In Fig. 3 a modification of the timing means of Fig. 1 is disclosed. In this modification the relay TX of Fig. 1 is omitted and the relay TZ is replaced by a relay TZ1 which is slow releasing in character. The operating winding of relay TZ1 is interposed in the circuit for the indication lamp L and hence the relay is energized and 20 picked up as long as the relay 2X is picked up. As set forth in describing the apparatus of Fig. 1, relay 2X is provided with a release period that is greater than the time interval between two successive check impulses and remains picked up as 25 long as the check impulses are properly received. The connection to the C terminal of the current source for the brake control apparatus is completed at the front contact 131 of relay TZ1. It follows that as long as the check impulses are 30 properly exchanged between the locomotive and the caboose and the relay 2X is picked up, the relay TZ1 is picked up and the control apparatus is operative, but that failure to receive a 35 check impulse which causes the relay 2X to release will in turn deenergize relay TZ1 and that relay will release at the expiration of its slow release period and render the control apparatus inoperative by opening the circuit connection to the terminal C of the current source. In Fig. 40 3 a manually operated push button 133 is provided for initially energizing relay TZ1 and thereby initially setting the apparatus into operation for exchanging check impulses. It is clear that with the locomotive equipment modified as disclosed in 45 Fig. 3 the operation of the system is essentially 50 the same as described hereinbefore.

Although I have herein shown and described only two forms of apparatus embodying my invention, it is understood that various changes 55 and modifications may be made therein within the scope of the appended claims without departing from the spirit and scope of my invention.

Having thus described my invention, what I 60 claim is:

1. In apparatus for communicating between two spaced locations over a single transmitting circuit the combination comprising receiving apparatus at one location coupled with the circuit 65 and effectively responsive to communication current of a predetermined frequency range, an auxiliary receiving means at said one location including a conductor coupled with the circuit and a frequency conversion unit effective to 70 convert a signaling current of a given frequency outside of said range to a current of a desired frequency within said range, and circuit means to couple the output side of said conversion unit with the input side of said receiving 75

apparatus to establish a signal peculiar to said signaling current.

2. In apparatus for telephone communication between two spaced locations over a single transmitting circuit the combination comprising receiving apparatus at one location coupled with the circuit and effective to demodulate and reproduce at a loud speaker the voice frequencies of a selected side band of a given carrier modulated by voice frequencies, an auxiliary receiving means at said one location including a conductor coupled with the circuit and a frequency conversion unit capable of converting a signaling current of a given frequency outside of said side band to a current of a desired frequency within said side band, and circuit means to couple the output side of said conversion unit with the input side of said receiving apparatus to establish a peculiar note at the loud speaker in response to such signaling current flowing in the transmitting circuit.

3. In apparatus for telephone communication between two spaced locations over a single transmitting circuit the combination comprising receiving apparatus at one location coupled with the circuit and effective to demodulate and reproduce at a loud speaker the voice frequencies of a selected side band of a given carrier modulated by voice frequencies, a frequency conversion unit at said one location and including an electron tube and a source of carrier current connected to one control grid of the tube, said unit effective to mix current from said source with a signaling current of a given frequency outside of said side band to convert the given frequency to a desired frequency within said side band, a first circuit means connected to another control grid of said electron tube and having a conductor coupled with the transmitting circuit, said first circuit means being tuned sharply at said given frequency, and a second circuit means to couple the plate circuit of said tube with the input side of the receiving apparatus and tuned to effectively pass said desired frequency whereby a peculiar note is sounded at the loud speaker in response to a signaling current of said given frequency flowing in the transmitting circuit.

4. In apparatus for communicating between two spaced locations over a single transmitting circuit the combination comprising equipment at each location each of which equipments includes transmitting apparatus capable of supplying to said circuit communication current of a predetermined frequency range and receiving apparatus effectively influenced by current of said frequency range flowing in said circuit, auxiliary receiving means at one of the locations including a conductor coupled with the circuit and a frequency conversion unit effective to convert a signaling current of a frequency outside of said predetermined frequency range to a current of a frequency within said range, circuit means to couple said conversion unit with the receiving apparatus to establish a signal peculiar to said signaling current, and means at the other location to supply at times such signaling current to the transmitting circuit.

5. In apparatus for communicating between two spaced locations over a single transmitting circuit the combination comprising equipment at each location each of which equipments includes transmitting apparatus capable of supplying to said circuit communication current of

a predetermined frequency range and receiving apparatus effectively influenced by current of said frequency range flowing in said circuit, auxiliary receiving means at one of the locations including a conductor coupled with the circuit and a frequency conversion unit effective to convert a signaling current of a frequency outside of said predetermined frequency range to a current of a frequency within said range, circuit means to couple said conversion unit with the receiving apparatus to establish a signal peculiar to said signaling current, and means at the other location to cooperate with the transmitting apparatus at said other location in supplying at times such signaling current to the transmitting circuit.

6. In apparatus for communicating between two spaced locations over a single transmitting circuit the combination comprising equipment at each location each of which equipments includes transmitting apparatus capable of supplying to said circuit communication current of a predetermined frequency range and receiving apparatus effectively influenced by current of said frequency range flowing in said circuit, switching means at each location to effectively couple either the transmitting apparatus or the receiving apparatus at the same location to said circuit, auxiliary receiving means at one of said locations including a conductor coupled to the circuit and a frequency conversion unit effective to convert a signaling current of a frequency outside of said predetermined frequency range to a current of a frequency within said range, circuit means to couple said conversion unit with the receiving apparatus to establish irrespective of the position of the associated switching means a signal peculiar to said signaling current, and means at the other location to supply at times such signaling current to the transmitting circuit.

7. In apparatus for telephoning between two spaced locations over a single transmitting circuit the combination comprising equipment at each location each of which equipments includes transmitting apparatus capable of supplying a selected side band of a given carrier current modulated by voice frequencies and receiving apparatus capable of demodulating such selected side band and reproducing the voice frequencies, switching apparatus at each location each operable to different positions to couple either the transmitting apparatus or the receiving apparatus to said circuit, auxiliary receiving means at one location including a conductor coupled with the circuit and a frequency conversion unit operable to convert a signaling current having a frequency outside of said selected side band to a predetermined frequency within said side band, circuit means to couple the conversion unit to the receiving apparatus to produce irrespective of the position of the switching apparatus at said one location a note peculiar to the signaling current, and means at the other location to cooperate with the transmitting apparatus to supply such signaling current to the circuit.

8. In apparatus for telephoning between two spaced locations over a single transmitting circuit the combination comprising equipment at each location each of which equipments includes transmitting apparatus capable of supplying a selected side band of a given carrier current modulated by voice frequencies and receiving apparatus capable of demodulating such selected side band and reproducing the voice frequencies,

- switching apparatus at each location each operable to different positions to couple either the transmitting apparatus or the receiving apparatus to said circuit, and break-in apparatus consisting of means at one location to cooperate with the transmitting apparatus to supply to the circuit signaling current of a frequency outside of said selected side band and a frequency conversion unit at the other location having its input side coupled with the circuit and its output side coupled with the receiving apparatus, said unit being operable to convert said signaling current to a current having a predetermined frequency within said side band.
15. 9. In apparatus for telephoning between two spaced locations over a single transmitting circuit the combination comprising equipment at each location each of which equipments includes a transmitting apparatus capable of supplying a selected side band of a given carrier current modulated by voice frequencies and receiving apparatus capable of demodulating such selected side band and reproducing the voice frequencies, switching apparatus at each location each operable to different positions to couple either the transmitting apparatus or the receiving apparatus to said circuit, and break-in apparatus consisting of means at one location to cooperate with the transmitting apparatus to supply to the circuit signaling current of a frequency outside of said selected side band and a frequency conversion unit at the other location and which unit includes an electron tube having its plate circuit coupled with the receiving apparatus, one control grid circuit coupled with the transmitting circuit and a second control grid connected with an oscillator supplying a carrier current which carrier when mixed with the signaling current produces a predetermined frequency within said side band.
40. 10. In apparatus for telephoning between two spaced locations over a single transmitting circuit the combination comprising equipment at each location each of which equipments includes a transmitting apparatus effective to supply the upper side band of a given carrier current modulated with voice frequencies and receiving apparatus effective to demodulate such upper side band and reproduce the voice frequencies, and a break-in apparatus consisting of means at one location for supplying to the transmitting circuit a current having a predetermined frequency above said upper side band and a frequency conversion unit at the other location including a source of carrier current which when mixed with said predetermined frequency produces a desired frequency within said upper side band, said unit having its input side coupled with the transmitting circuit and its output side coupled with the input side of the receiving apparatus.
45. 11. In apparatus for telephoning between two spaced locations on a railway train the combination comprising equipment at each location each of which equipments includes transmitting apparatus capable of supplying a selected side band of a given carrier current modulated with voice frequencies and receiving apparatus effective to demodulate such selected side band and reproduce the voice frequencies, manually operable switching means at each location to selectively couple either the transmitting apparatus or the receiving apparatus to the track rails, and break-in apparatus consisting of means at one location for supplying to the rails a current of a predetermined frequency outside of said selected side band and a frequency conversion unit at the other location operable to convert said predetermined frequency to a desired frequency within said side band, said unit having its input side coupled with the track rails through a circuit tuned at said predetermined frequency and its output side coupled with the receiving apparatus through a circuit tuned at said desired frequency.
5. 12. In apparatus for communicating between two spaced locations over a single transmitting circuit the combination comprising transmitting apparatus at one location coupled with the circuit, said apparatus having a telephone condition in which it is effective to supply a selected side band of a given carrier modulated at voice frequencies and a control condition in which it is effective to supply a current of a predetermined frequency outside of said side band coded at different control codes in accordance with different positions of a control member, receiving apparatus at the other location operable to demodulate said selected side band, a loud speaker and a control circuit network connected in parallel to the output terminals of the receiving apparatus, said network selectively responsive to a desired voice frequency when coded in accordance with said control codes, a frequency conversion unit at said other location effective to convert said predetermined frequency to a frequency within said side band and which frequency is equal to said carrier modulated by said desired voice frequency, means to couple the output of said unit with the input of the receiving apparatus, a first circuit to couple the input of the receiving apparatus with the transmitting circuit for receiving the telephone current, and a second circuit to couple the input of the conversion unit with the transmitting circuit for receiving the control current.
10. 13. In combination, receiving apparatus effective to demodulate a selected side band of a given carrier modulated by voice frequencies, a loud speaker and a control circuit network connected in parallel with the output terminals of said receiving apparatus, said control network selectively responsive to a given voice frequency when coded at different control codes, a frequency conversion unit including a source of carrier current and an electron tube the plate circuit of which is coupled with the input of the receiving apparatus, said unit effective to mix current from said source with a control current of a predetermined frequency outside of said side band to convert said predetermined frequency to a frequency within the side band and which latter frequency is equal to said given carrier modulated by said given voice frequency, a first receiving circuit tuned to effectively pass said side band and connected with the input of the receiving apparatus for receiving a telephone current, and a second receiving circuit tuned sharply at said predetermined frequency and connected with the input of said conversion unit for controlling said control network by coded control current.
15. 14. In apparatus for communicating between two spaced locations the combination comprising, control apparatus partly at each of said locations and effective to cause an operating mechanism at one location to register with different positions of a control member at the other location, checking means partly at each location to cause said control apparatus to exchange between the two locations check impulses to check the integrity of said control apparatus, said checking means including a timing device located at said other location and effective when operated a pre-
20. 25. 30. 35. 40. 45. 50. 55. 60. 65. 70. 75.

- determined time interval to initiate the sending of a check impulse and to maintain the sending of such impulse until the receipt of a return check impulse from said one location, and means controlled by each such return impulse to initiate a new operation of the timing device.
15. In apparatus for communicating between two spaced locations the combination comprising, control apparatus partly at each of said locations and effective to cause an operating mechanism at one location to register with different positions of a control member at the other location, checking means partly at each location to cause said control apparatus to exchange between the two locations check impulses to check the integrity of said control apparatus, said checking means including a timing device located at said other location and effective when operated a predetermined time interval to initiate the sending of a check impulse and to maintain the sending of such impulse until the receipt of a return check impulse from said one location, and means controlled by each such return impulse to initiate a new operation of the timing device, and a delayed action means associated with said timing device and operative a given period after the device has completed an operation to render the control apparatus inoperative.
20. In apparatus for communicating between two spaced locations the combination comprising, control apparatus partly at each of said locations and effective to cause an operating mechanism at one location to register with different positions of a control member at the other location, checking means partly at each location to cause said control apparatus to exchange between the two locations check impulses to check the integrity of said control apparatus, said checking means including a first and a second timing device and both of which devices are located at said other location, said first timing device effective when operated a predetermined time interval to initiate the sending of a check impulse and to maintain the sending of such impulse until the receipt of a return impulse from said one location, said second timing device effective when operated for a time interval greater than said predetermined interval to render the control apparatus ineffective, and means controlled by each return impulse to initiate a new operation of each of said timing devices.
25. In apparatus for communicating between two spaced locations the combination comprising, control apparatus partly at each of said locations and effective to cause an operating mechanism at one location to register with different positions of a control member at the other location, checking means partly at each location to cause said control apparatus to exchange between the two locations check impulses to cause said control apparatus to exchange between the two locations check impulses to check the integrity of said control apparatus, said checking means including a first and a second slow pickup relay and both of which are located at said other location, said first relay having a relatively short pickup period and effective when picked up to initiate the sending of a check impulse, said second relay having a relatively long pickup period and effective when picked up to render the control apparatus inoperative, and means controlled by each return impulse received at said other location to reset and initiate a new operation of each of said relays.
30. In apparatus for communicating between two spaced locations over a single transmitting circuit, a source of current of one frequency at one location and a source of current of a second frequency at the other location, receiving apparatus at each location each coupled with said circuit, the receiving apparatus at said one location responsive to current of said second frequency and the receiving apparatus at said other location responsive to current of said one frequency, timing means at said one location effective when energized a predetermined time interval to cause the associated source to supply current to the transmitting circuit for influencing the receiving apparatus at said other location, means controlled by the receiving apparatus at said other location when influenced to display a signal and to cause the associated source to supply current to the circuit for influencing the receiving apparatus at said one location, and means controlled by the receiving apparatus at said one location when influenced to display a signal and to reset the timing means at its initial position.
35. In apparatus for communicating between two spaced locations on a railway train the combination comprising, transmitting and receiving apparatus at each of said locations and effective to establish any one of several different operating conditions for the train at each of said locations, means to cause said apparatuses to exchange check impulses between said locations and including a timing device at one location operable when energized a predetermined time interval to initiate the sending of a check impulse from said one location and to maintain the sending of such impulse until the receipt of a return check impulse from the other location, and means at said one location controlled by each return check impulse to initiate energization of said timing device.
40. In apparatus for communicating between two spaced locations the combination comprising, transmitting and receiving apparatus at each of said locations and effective to establish any one of several different operating conditions for the train at each of said locations, means to cause said apparatuses to exchange check impulses between said locations and including a timing device at one location operable when energized a predetermined time interval to initiate the sending of a check impulse from said one location and to maintain the sending of such impulse until the receipt of a return check impulse from the other location, and means at said one location controlled by each return check impulse to initiate energization of said timing device.
45. In apparatus for communicating between two spaced locations the combination comprising, transmitting and receiving apparatus at each of said locations and effective to establish any one of several different operating conditions for the train at each of said locations, means to cause said apparatuses to exchange check impulses between said locations and including a timing device at one location operable when energized a predetermined time interval to initiate the sending of a check impulse from said one location and to maintain the sending of such impulse until the receipt of a return check impulse from the other location, and means at said one location controlled by each return check impulse to initiate energization of said timing device.
50. In apparatus for communicating between two spaced locations the combination comprising, transmitting and receiving apparatus at each of said locations and effective to establish any one of several different operating conditions for the train at each of said locations, means to cause said apparatuses to exchange check impulses between said locations and including a timing device at one location operable when energized a predetermined time interval to initiate the sending of a check impulse from said one location and to maintain the sending of such impulse until the receipt of a return check impulse from the other location, and means at said one location controlled by each return check impulse to initiate energization of said timing device.
55. In apparatus for communicating between two spaced locations the combination comprising, transmitting and receiving apparatus at each of said locations and effective to establish any one of several different operating conditions for the train at each of said locations, means to cause said apparatuses to exchange check impulses between said locations and including a timing device at one location operable when energized a predetermined time interval to initiate the sending of a check impulse from said one location and to maintain the sending of such impulse until the receipt of a return check impulse from the other location, and means at said one location controlled by each return check impulse to initiate energization of said timing device.

LELAND D. WHITELOCK.
